UNITED STATES PATENT OFFICE.

WILLIAM H. KAMMAN, OF BURLINGTON, IOWA.

FOOD-DISPLAY RACK.

Application filed April 21, 1927. Serial No. 185,550.

This invention relates to improvements in food display racks, particularly in a supporting device adapted to display bananas or other suitable fruits and foods.

- 5 An object of this invention is to provide a display rack of a foldable type and made in sections so that it can be utilized either as disclosing the food as a window display or on the sidewalk or in any open place.
- 10 It has been found in the care and sale of fruits, bananas particularly, that when placed on the ordinary supports in a window or otherwise where they are subjected to cold and heat, they become over-ripe or chilled.
- 15 In order to overcome these disadvantages, this invention provides a means to overcome the trouble and still display the food, as well, if not better, than the old method commonly in use, such as a rope and pulley.
- 20 Other objects of this invention will be found in the following detailed description of the device, and as disclosed in the single sheet of drawings which is herewith made a part of this application.

- 25 In the drawings,

Figure 1 illustrates a perspective view of the food display rack.

Figure 2 represents a perspective view of the upper portion of the food display rack, in foldable condition.

Figure 3 illustrates a perspective view of the base portion of the display rack, disclosing the portion in foldable condition.

35 Numerals 1, 2 and 3 designate the frame work of the upper portion of the display rack which may be made of any suitable material such as rods bent into proper shape for the purpose, the upper ends of the rods 1, 2 and 3 being adapted to extend through suitable openings in a plate 4 and fastened thereto by means of bolts 5 and 6 or otherwise. Extending downward from the plate 4 is a hook or other supporting means 7 adapted for the purpose of carrying a food display, such as bananas 8 as disclosed in Figure 1, it being understood that the food display rack in this invention may be utilized in connection with any suitable display. The lower ends of the rods 1, 2 and 3 are adapted to be attached to yoke pieces 9 and 10 in any suitable manner as by means of lock nuts 11, 12 and 13, two of the rods being connected to one of the yoke members, such as 10, while one of the rods is connected to the other yoke member 9 at one end thereof, the other end 14 of the yoke member 9 being allowed

to swing free and of suitable shape for use as a handle.

The food display rack, according to this invention, is preferably made of two main portions, the upper portion having been described in substance as above, and both portions being of a foldable type. The lower portion comprises two main elements 15 and 16 made from any suitable material such as 60 wrought iron and bent into the form of a supporting stand for the upper portion of the display rack, the stand having leg portions 17, 18, 19 and 20 adapted to be suitably braced by means of cross rods 21 and 22 attached 65 near the lower ends thereof. The elements 15 and 16 are pivotally and foldably joined as at 23 by means of a lock nut and shank portion 24 and a thumb screw 25 for the purpose of placing tension between the two elements. The lock nut and shank elements 24 are adapted to extend upward a sufficient distance to receive the coacting element 26 in the upper portion of the food display rack 70 in pivotal relationship thereto. The washer 75 or lock nut element 26, being located at the pivoting point between the yoke members 9 and 10, and as the shank member 24 extends through the elements 9, 10 and 26, it is adapted to receive a thumb screw or 80 other suitable element 27, thereby providing a device which will function through the means of thumb screws 25 and 27 to produce 85 the desired tension between the upper and lower units of the display rack, thereby 90 allowing the upper portion to revolve as may be desired.

For convenience, a plate shelf 28 is preferably located at the lower end of the upper unit of the display rack directly above the 95 yoke elements 9 and 10, and supported thereby, it being held in rigid relationship to the remaining portions of the rack by means of the thumb screw 27 and shank portion 24, which is adapted to pass through a suitable 100 opening in the plate 28.

In operation, this invention provides a food display rack, particularly adaptable for the display of bananas, and functions to allow the fruit to be shown to advantage in a 105 window where they might be subjected to cold and heat. The rack, together with the food display, can be easily changed in location without inconvenience. The stand being built in two main units makes it possible 110 to use the rack for various purposes, such as window and sidewalk displays, the window

display requiring merely the upper half of the device in many instances, while the sidewalk or outside display would ordinarily require both the lower and upper sections properly joined together. One of the great advantages of this device is the foldable construction and the ease with which the various portions can be assembled and securely fastened so that they will not move in relationship to each other or otherwise, as may be desired.

The device is simple of manufacture and inexpensive, consisting of a minimum number of elements bent into proper shape and held in this condition by a small number of cross rods. It is apparent that the upper portion of this display rack may be easily separated from the lower portion by manipulating the thumb screws and can then be set 15 in the window, or even on a counter, or such location as desired, while the foldable nature of the device will allow of its being stored or shipped with the least possible difficulty.

The plate at the lower end of the upper 25 portion is adapted for use as a holder for loose fruit and food, or for any other suitable purpose.

What I claim is:—

1. A food display rack comprising detachable upper and base portions, means for pivotally mounting the upper portion on the base portion, a supporting element in the

upper portion from which to suspend a food display, a plate shelf positioned in the lower end of the upper portion, the upper portion of the rack consisting of a plurality of rod elements bent into suitable form, a plate to which the upper ends of the rods are fastened, the supporting element being suspended therefrom, foldably arranged cross bars for receiving the lower ends of the rods, a pivotal connection between the bars and upper plate for allowing the rack to fold.

2. A food display rack comprising detachable upper and base portions, means for pivotally mounting the upper portion on the base portion, a supporting element in the upper portion from which to suspend a food display, a plate shelf positioned in the lower end of the upper portion, the upper portion of the rack consisting of a plurality of rod elements bent into suitable form, a plate to which the upper ends of the rods are fastened, the supporting element being suspended therefrom, foldably arranged cross bars for receiving the lower ends of the rods, a pivotal connection between the bars and upper plate for allowing the rack to fold, the base portion comprising a plurality of bar elements bent into suitable form and foldably arranged in respect to each other.

In testimony whereof I affix my signature.

WILLIAM H. KAMMAN.
